UNITED STATES PATENT OFFICE.

JOHN M. BROWN AND NATHAN G. BOGGS, OF HAMILTON, CANADA.

CORNICE AND EAVES-TROUGH BRAKE MACHINE.

SPECIFICATION forming part of Letters Patent No. 471,599, dated March 29, 1892.

Application filed August 3, 1891. Serial No. 401,451. (No model.)

To all whom it may concern:

Be it known that we, JOHN M. BROWN and NATHAN G. BOGGS, citizens of Canada, residing at Hamilton, in the county of Wentworth, in the Province of Ontario, Dominion of Canada, have invented a new and useful Improvement in Cornice and Eaves-Trough Brake Machines, of which the following is a specification.

- 10 Our invention relates to improvements in cornice and eaves-trough brake machines, in which the same is used principally for bending and curving tin, galvanized iron, and sheet metal for cornice purposes chiefly.
- 15 The principal feature and element in this invention consists in what is termed technically the "fourth leaf," which is adjustable to various diameters and when in operation on its end centers or pivots brakes over the forms of the common cornice-brake machine, thus accomplishing or forming a circular bend over the various shapes and sizes of forms that may be attached and adjusted to the brake-machine proper.
- 20 The objects of our improvements are, first, to provide means to form curves and circular bends in eaves-troughs, cornices, and other articles of like nature; second, to afford facilities for the proper adjustment of the fourth leaf to various distances or radii from its center to act independently of any other component part of the machine, yet at the same time in conjunction or combination with the same, and, third, to apply this fourth-leaf brake to the now-existing cornice-brake machines, pivoted on bearings of the front, bottom, or top leaves, for the purpose herein set forth, this third object being a very practical and important feature in this invention. We 25 attain these objects by the mechanism illustrated in the accompanying drawings, in which—

Figure 1 is a front elevation of a cornice-brake machine having our fourth leaf with its two end swivel attachments in position. Fig. 2 is an end elevation of the same, showing very fully a segment of a circle which forms a part of end swivels of fourth leaf for the purpose of steadyng and equalizing the ends of the same when in operation. Fig. 3 shows an end section of the front leaf and

fourth leaf through the broken line x x , having a form clamped in position. Fig. 4 is an enlarged end elevation of the front leaf, showing a clamp with its fulcrum and eccentric handle in working position. Fig. 5 is a front elevation of the same clamp detached; and Fig. 6 is a front elevation of the detached eccentric handle, also enlarged.

Similar letters refer to similar parts throughout the several views.

The metal frame or legs A and the front leaf B, with its journals c in the bearings a of said frame A, form the essential elements in an eaves-trough and cornice brake machine. 65 On these two journals c of the front leaf B are the two end swivel attachments D D, which for purposes of ready removal may be provided with caps on their under side. These attachments D D are allowed to swivel when 70 operating the fourth leaf, and their longitudinal rod d acts as a handle and also for steadyng purposes. The fourth leaf E is connected and journaled to the said swivel end attachments by means of the longitudinal rod F, 75 which passes through the three standards H of said leaf E and into its flanged bearings I, the said leaf E being adjusted to its proper radii from its center bearings by means of the vertical screws J, which are screwed through 80 the upper parts of said swivels, then pass downward through an opening in the swivels into, and secured to the flanged bearings I. Thus the weight of the leaf E is supported, 85 adjusted, and regulated by the said screws J, which are operated by their hand-wheels K. This leaf E is also provided with a catch e at each end to allow said leaf to be locked to a certain position in relation to said swivels. The leaf E can also be thrown back when not 90 in use, so as not to interfere with the ordinary operation of the machine. When operating the said leaf E and in order to bring both ends of the same to a parallel position to the rest of the machine, the said swivels D are each 95 provided with a circular segment L, cast to or attached thereto, and is allowed to engage with the toothed wheels m, which are journaled on the longitudinal shaft s, supported in the bearings n, which are placed on the 100 upper part of the frame or legs A of the machine. The practicability of these two toothed

segments, as hereinbefore mentioned, will be perceptible, because it will be noticed that when the machine is many times the length, as shown, it will be impossible for one end of the leaf E to gain or to at all be out of a parallel position to the machine on account of the pinion-wheels *m*, engaged in the segment L, being secured to their common longitudinal and parallel shaft *s*.

10 The four small clamps which are attached to the front leaf B each consists of three pieces—namely, the clamp O, the T-headed bolt T, and the eccentric handle U—of which a set is seen very fully in Fig. 4 of the drawings in position to secure various forms or shapes P, that are used for producing various curves of work. The upper end of clamp O is the part which secures the said forms to the front leaf by means of the eccentric handle, which when the upper part is brought down the lower or eccentric part presses against the leaf, thus bringing out the lower part of the clamp, and at the same time the upper part of said clamp presses against the forms or shapes P, the result being that the said forms are held in a rigid position against the front leaf. The bolt T acts as a fulcrum for the clamp and is adjustable by means of its nut to allow different thicknesses of forms 30 to be placed between the upper or binding part of clamp and leaf.

To these ends our invention consists in its mechanical construction and combination of its several parts to perform a parallel and circular motion, thus producing lengths of thin metal of various shapes and diameter of

curves requisite for building and other purposes.

What we claim as our invention, and desire to secure by Letters Patent, is—

1. In a cornice-brake machine, the combination, with the frame A, of the swivel attachments D D, carrying the brake and connected together by means of the longitudinal steady-rod *d* and journaled at *c*, each of said attachments provided with a toothed segment cast thereto or otherwise attached concentrically with said journals *c* and geared into pinions *m*, secured to their longitudinal shaft *s* in bearings *n* of frame A, thus producing a uniformity of action and equalizing of the work, substantially as specified and set forth. 40

2. In a cornice-brake machine, the frames A, having bearings *a* and *n*, the front leaf B, having journals *c*, which work in said bearings *a*, and provided with the device consisting of the clamp O, T-headed bolts T, and eccentric handle U for holding in position the various shapes and forms on the front leaf, in combination with the swivel attachments D, connected by rod *d* and provided with the adjustable vertical bearings I, regulated by the screws J, the adjustable leaf E, having longitudinal rod F passing through the upper part of the same, and the lock *e* for fastening the said leaf E to swivels D, all substantially as set forth. 55

JOHN M. BROWN.
NATHAN G. BOGGS.
